UNITED STATES PATENT OFFICE.

WALLACE B. PIGG, OF CALHOUN, MISSOURI.

DESIGN FOR A KITCHEN-CABINET.

SPECIFICATION forming part of Design No. 26,416, dated December 15, 1896.

Application filed November 10, 1896. Serial No. 611,677. Term of patent 7 years.

To all whom it may concern:

Be it known that I, WALLACE B. PIGG, a citizen of the United States, residing at Calhoun, in the county of Henry and State of Missouri, have invented and produced a certain new and original Design for Kitchen-Cabinets; and I do declare the following to be a full, clear, and exact description of the invention, such as will enable others skilled in the art to which it appertains to make and use the same.

My invention has relation to a design for a kitchen-cabinet.

It relates to the entire construction of the cabinet, and especially to a kitchen-cabinet constructed of wood.

My invention relates particularly to the cabinet as illustrated in the accompanying drawing, in which the figure is a perspective view of a kitchen-cabinet embodying my design.

The leading features of my design appear in the following description.

A represents the legs; B B, the semicircular or curved drawers; C, the horizontal plane 25 top; D, the approximately rectangular back, having the central ornamental crown-piece E, the inverted or curved scrolls F F, and the ornamental crown end pieces G G.

Having thus described my design, what I 30 claim, and desire to secure by Letters Patent of the United States, is—

The design for a kitchen-cabinet, substantially as herein shown and described.

In testimony whereof I hereunto affix my 35 signature in presence of two witnesses.

WALLACE B. PIGG.
